UNITED STATES PATENT OFFICE.

DAVID A. CLARK, OF ST. LOUIS, MISSOURI, ASSIGNOR OF ONE-HALF TO
FRANK T. FLETCHER, OF SAME PLACE.

TOY PISTOL.

SPECIFICATION forming part of Letters Patent No. 281,455, dated July 17, 1883.

Application filed April 5, 1883. (No model.)

To all whom it may concern:

Be it known that I, DAVID A. CLARK, of the city of St. Louis, in the State of Missouri, have invented a certain new and useful Improvement in Toy Pistols, of which the following is a full, clear, and exact description, reference being had to the accompanying drawings, forming part of this specification, and in which—

10 Figure 1 is a longitudinal section, showing the parts in firing position. Fig. 2 is a similar view, showing the parts after firing. Fig. 3 is a front view. Fig. 4 is an enlarged detail view; and Fig. 5 is a vertical section taken on line 5 5, Fig. 4, showing the concussion-cap-receiving chamber, with its side opening.

15 My present invention relates to an improvement on the pistol for which Letters Patent of the United States were issued to myself and assignee, Frank T. Fletcher, 13th of March, 1883, No. 273,956; and this invention consists in points of novelty hereinafter fully described, and pointed out in the claims.

20 Referring to the drawings, A represents the body of the pistol, which is similar to that shown and described in the patent mentioned.

25 B represents the plunger; C, the hammer; D, the sear, and E the trigger. The trigger and sear are formed in one piece, which is pivoted 30 to the body at F. The hammer has notches G, with which the sear is made to engage by means of a spring, H, one end of which bears against the under side of a projection, I, of the sear. The other end of the spring H extends 35 into the barrel of the pistol for the purpose of holding the marble J in place before firing. This spring is preferably secured in place by passing or being inserted in a serpentine groove, K, in the body of the pistol, as shown 40 in Figs. 1 and 2. The spring is thus securely held from any end movement, and its ends are free to perform their respective duties, the construction being cheap, simple, and durable.

45 The plunger is formed of a plain piece of bent wire, which is hooked over a horn, L, of the hammer, and has secured to its outer ends a disk, M, against which the marble rests before firing, as shown. The plunger works through

a slot or perforation in the breech of the pistol, and is thus guided and held in its proper 50 position. The hammer works in a vertical opening in the breech of the pistol, as shown. The slot in which the plunger works is formed by ribs N in the vertical walls of the opening in which the hammer works, the ribs being 55 on the two parts of the body of the pistol, and there being space enough between them (see Fig. 5) for the passage of the horn L as the hammer is cocked and the pistol fired. By having the plunger pass through the breech 60 of the pistol a good guide is had, and the barrel of the pistol can be made quite short.

65 O represents the spring that surrounds the plunger and throws it forward when the pistol is fired.

P represents a chamber having inner chamber, P', beneath the opening, to receive and retain a concussion-cap, which is struck by the hammer when the pistol is fired. (See Fig. 2.) The opening Q to this chamber, through 70 which the cap is inserted, is in the side, instead of on top, as usual, so that there is no danger of part of the cap flying and striking the person firing the pistol in the face.

75 I claim as my invention—

1. In a toy pistol, the combination, with a spring extending from the sear through the bottom of the barrel, to hold a marble in firing position and the sear in contact with the 80 hammer, as set forth.

2. In a toy pistol, the combination of sear, hammer, plunger, barrel having serpentine grooves K, and spring extending from the sear through said grooves, with the barrel to hold 85 a marble in firing position and the sear in contact with the hammer, as set forth.

3. In a toy pistol, the combination of sear, hammer, plunger, and barrel A, having hollow breech formed with horizontal guides N 90 for the plunger within the breech, the plunger being engaged with a horn on the hammer, both in loading and firing positions of the parts, as set forth.

4. In a toy pistol, a body, A, having a 95 breech formed with cap-opening Q at the side,

chamber P, and inner chamber, P', to retain the cap, in combination with suitable hammer, sear, and trigger, as set forth.

5. In a toy pistol, the combination of body A, plunger B, spring O around the plunger, hammer C, having horn L, engaging plunger and notches G, combined sear and trigger D

E, having projection I, and spring H, extending from the projection through the bottom of the body to retain a marble, as set forth.

DAVID A. CLARK.
